Des. 183,954
Patented Nov. 18, 1958

183,954

COMBINED DENTAL LAMP AND SUPPORT OR THE LIKE

Frederick K. Storm, Jr., Los Angeles, and Eldridge H. Smiley, Rosemead, Calif., assignors, by mesne assignments, to American Sterilizer Company, Erie, Pa., a corporation of Pennsylvania

Application August 19, 1957, Serial No. 47,456

Term of patent 14 years

(Cl. D48—20)

Fig. 1.

Fig. 2.

Fig. 3.

Fig. 1 is a side elevational view of a combined dental lamp and support embodying our new design;

Fig. 2 is a top plan view thereof; and

Fig. 3 is a front elevational view thereof.

The opposite side of the combined dental lamp and support is substantially the same in appearance as the side shown.

We claim:

The ornamental design for a combined dental lamp and support or the like, substantially as shown and described.
